UNITED STATES PATENT OFFICE

2,639,608

BRICK AND TILE LAYING MACHINE

John D. Kirschmann, Regent, N. Dak.

Application June 17, 1948, Serial No. 33,471

4 Claims. (Cl. 72—129)

1

This invention comprises novel and useful improvements in a brick and tile laying machine and more specifically pertains to a mechanism for assisting in constructing brick and tile walls and particularly in applying a layer of mortar to the top course brickwork, forcing the mortar into the joints between adjacent bricks in the top course and applying an additional course of bricks in properly spaced relation to each other and to the top course.

An important object of the invention is to provide a brick laying machine which will assist in laying bricks and tiles in brickwork construction, with ease, accuracy and a saving in time and labor.

A further object of the invention is to provide an apparatus as set forth in the preceding object, which may be easily and readily applied to or removed from brickwork constructions; which may be readily adjusted to accommodate different sizes and proportions of brick work constructions; and which is capable of maintaining a predetermined vertically spaced relation between the successive courses of brickwork with which the machine is employed.

An important feature of the invention resides in the provision of a framework including transverse clamp bars, depending parallel vertically extending side walls pivoted to the bars together with spring means for urging the side walls toward each other, accompanied by support members for mounting the side walls above the top course of a brickwork construction and for supporting the side walls from a lower course of brickwork.

Another important feature of the invention resides in the provision of an apparatus as set forth in the preceding feature wherein means are provided for longitudinally and vertically adjusting the support members with respect to the side walls; and wherein handle means are provided for quickly and easily pivoting the side walls and the supporting members carried thereby to facilitate application of the apparatus to a brickwork construction or removal of the same therefrom.

A still further feature of the invention resides in the provision of an apparatus as set forth in the preceding objects and features wherein the side walls are provided with inwardly extending flanges rigidly attached at their lower ends and constituting guide means, which flanges serve the dual purpose of supporting an additional course of brickwork in predetermined vertically spaced relation with respect to the top course

2

thereof, and also provide means for supporting and providing longitudinal movement of a mortar applicator.

A still further important feature of the invention resides in the provision of an apparatus as set forth in the above mentioned features and objects, wherein the mortar applicator includes a hopper movable longitudinally of the side walls, and mounted therebetween; and which hopper is provided with a combined dispensing and leveling opening for applying a layer of mortar to the top course of brickwork; together with a mortar tamping means for forcing mortar into the joints between adjacent bricks of the top course of the brickwork.

Yet another feature of the invention resides in the provision and appliance as set forth in the foregoing features and objects of the invention, wherein the mortar applicator includes packing and sealing means for confining the layer of mortar to be applied to a predetermined portion of the top surface of the top course of brickwork; and wherein the joint or crack filler of the mortar applicator includes a transversely extending tubular member having an open lower end together with a reciprocable plunger in said tubular member, said tubular member and plunger being mounted upon a common fulcrum pin carried by the applicator.

Yet another important feature of the invention resides in the provision of an appliance in conformity with the above mentioned features and objects wherein there is provided an improved ruler mounted upon one of the side walls for assisting in maintaining even longitudinal spacing of the successive bricks in a course; wherein there is provided an improved and novel mounting of spirit levels on the side walls of the device; and wherein is provided an attachment for enabling the constructing of combination tile and brickwork walls.

These, together with various ancillary features and objects of the invention which will later become apparent as the following description proceeds, are attained by this device, preferred embodiments of which have been illustrated by way of example only in the accompanying drawings, wherein:

Figure 1 is a top plan view showing a preferred embodiment of the device, parts being broken away;

Figure 2 is a side elevational view of the arrangement shown in Figure 1;

Figure 3 is a fragmentary detail view taken upon an enlarged scale substantially upon the

vertical plane through the section line 3—3 of Figure 2 and showing in particular the guide flanges of the side walls for supporting an additional course of brickwork together with the pivotal and resilient mounting of the side walls;

Figure 4 is a view taken in elevation and at right angles to Figure 3;

Figure 5 is a view similar to Figure 3, but showing a construction suitably proportioned for constructing a brick wall that is two thicknesses of brick in width;

Figure 6 is an elevational view, upon an enlarged scale of a portion of the construction shown in Figure 2, and illustrating in particular the clamping means of the support means of the frame of the device;

Figure 7 is a view in vertical section through the detail view of Figure 6, and is taken substantially upon the vertical plane of the section line 7—7 of Figure 2, and with Figure 6 illustrates in particular the manner of supporting the side walls of the frame from and upon a lower course of the brickwork construction;

Figure 8 is an enlarged detail view taken in elevation of a portion of the device shown in Figure 2, this view illustrating the abutment means for adjusting the vertical inclination of the side walls of the device;

Figure 9 is a vertical sectional view through the construction of Figure 8, taken substantially upon the vertical plane of the section line 9—9 of Figure 2;

Figure 10 is a fragmentary detail view taken upon an enlarged scale in elevation of a portion of the rule and its fastening means;

Figure 11 is a fragmentary vertical transverse sectional view taken substantially upon the plane of the section line 11—11 of Figures 2 and 10;

Figure 12 is a side elevational view showing a tile setting attachment for use with this invention;

Fig. 13 is a longitudinal sectional view through a portion of the machine, showing the construction of a mortar applicator and its attachment thereto;

Figure 14 is a vertical transverse sectional view taken substantially on the plane of the section line 14—14 of Figure 2; and,

Figure 15 is a fragmentary view similar to Figure 13 but showing the crack filling means in depressed position.

Referring now more specifically to the accompanying drawings, wherein like numerals designate similar parts throughout the various views, there is disclosed in Figure 2 a brickwork construction, a wall portion consisting of a plurality of courses of brick, these courses being indicated at 10, and this brickwork terminating in a top course 12. The brick laying machine forming the subject of this invention is shown in Figures 1 and 2 as applied in operative position to the courses of brickwork, for the purpose of facilitating the proper assembling of bricks and laying of successive courses of brickwork upon the brickwork construction.

It is to be here understood that the principles of the invention are equally applicable to walls consisting of a single layer of brick, in the manner shown in Figure 3, or to constructions consisting of a plurality of layers of brick to each course, such as shown in Figure 5. Since the principles of the two embodiments are identical, the device is shown throughout the drawings as applied to a wall consisting of a single thickness of brick.

As will be best understood by reference to Figures 1—4, the brick laying machine consists essentially of a pair of transverse end or clamp bars 14, each bar consisting of a pair of parallel plates, between the extremities of which are pivotally connected as at 16, a pair of levers 18, intermediate the ends of the latter. The upper ends of these levers are provided with handle portions 20 for manipulating the same while the lower ends of the levers are rigidly secured as by bolts 22 to the vertically disposed walls 24 forming part of angle iron members whose horizontal lower flanges or walls are indicated at 26. The vertical walls 24 constitute the side walls of the frame of the brick laying machine.

Conveniently mounted upon the transverse or clamp bars 14, are conventional spirit levels 28, and further conventional spirit levels 30 are mounted upon the horizontal flange portions 26 of the angle iron frame members, these spirit levels assisting in placing the frame work in proper leveled position upon a course of brick-work.

Pivoted as at 32, see both Figures 3 and 5, are 25 a pair of arcuate bolts 34 upon which are received compression springs 36, and which bolts extend through suitable apertures in the upper ends of the levers 18, suitable lock nuts 38 being mounted upon the screw threaded extremity 40 of the bolts 34, these lock nuts regulating the outer pivotal movement of the lever in response to the resilient urging of the springs 36. It should be here noted that the arrangement is such that these springs urge the two levers in 35 a direction as to bias the two side wall members 24 toward each other in a manner and for a purpose to be set forth hereinafter.

Preferably integrally attached as by welding or the like to the side members 24 at their lower 40 ends, are a pair of inturned flanges 42 which constitute guide means for a purpose to be set forth hereinafter.

Support means are provided by means of which the angle iron and their side wall members are 45 adjustably mounted upon and secured to the brickwork construction with which the machine is to be used. These support members, whose construction is shown best in Figures 2, 6 and 7, consist of carriages, each of which comprises 50 upper and lower plates 44 and 46 respectively which slidably embrace the upper and lower surfaces of the horizontal flange 26 of the angle iron frame member, these upper and lower plates being rigidly secured to each other and to an 55 intermediately extending plate member 48, as by welding or the like, whereby a rigid slide is provided which is movable longitudinally of the horizontally extending flange member 26 of the frame. In order to secure each of these carriages 60 at predetermined desired positions along the horizontal flange of the frame member, set screws 50 and lock nuts are provided, the set screws being carried by and extending through the upper plate 44 into engagement with the horizontal 65 flange 26 which is embraced by the upper and lower plates. A generally U-shaped standard or support 52 is carried by and extends above the upper plates 44, this standard being provided with a vertical bore 54. An adjusting screw 56 is rotatably but non-slidably received in the bore 54 by means of a collar 58 and a head portion 60 having a handle or finger grip member 62 carried thereby. Thus, the adjusting screw 56 is free to rotate but is held immovably with respect to the supporting bracket 52.

Depending from and adjustably carried by the adjusting screw 56, is a support rod 64, having the laterally extending lower arm 66, with a toe 68 adapted to penetrate the joint between a pair of adjacent courses of brickwork, which toe rests upon the edge of the upper surface of course 10 or 12, depending upon the length of the rod 64. The upper end of the rod 64 is provided with an inturned portion or flange 10 which is screw-threadedly engaged by the screw 56, whereby upon rotation of the latter, the rod 64 is raised or lowered.

A longitudinally extending slot 72 is provided between the intermediate plate 48 and the adjacent outer edge of the flange 26. The rods 64 and 65 are thus slidably disposed in slot 72, for vertical movement in response to manipulation of the adjusting screw 56 by the handle 62.

It is to be here observed that the function of the adjusting screw is to regulate the height at which the side walls of the frame members are positioned with respect to the top course 12, whether supported directly thereon or on the course immediately therebeneath; in order that the guide members 42 may be vertically spaced a predetermined distance above the top surface of the top course 12. This predetermined vertical space is desirable in that it permits and assures an even thickness of mortar layer between the successive courses, in a manner to be subsequently apparent, and thus greatly improves the ease and quality of the work performed by the machine.

Obviously, any desired number of these carriage support members may be provided depending upon the length of the angle iron frame members, and the type of work being performed.

In order to steady the frame members of the machine upon the brickwork construction, and plumb the same, a lateral supporting means or abutment is provided. This means comprises a plurality of downwardly extending channel shaped members 74, see Figures 8 and 9, which at their upper ends are secured as by fastening means 76 to one end of a laterally extending body 78, whose other end rigidly positioned as at 80 between a pair of support brackets 82 of L-shaped construction, which brackets form part of the adjustable clamp which is slidably longitudinally of and embraces the above-mentioned flange 26 of the frame members.

For this purpose, the brackets 82 terminate in horizontally disposed plates 84 at their lower ends, which plates are slidably received upon the upper surface of the flange 26 as shown in Figures 8 and 9. Similar plates 86 underly the flange 26, and are disposed beneath the plates 84, and are secured to intermediate connecting members 88 which are horizontally aligned with the adjacent edge of the flange 26, the members 84, 86 and 88 being attached to each other as by welding or the like, to form a clamp for slidably embracing the flange 26. A set screw means 90 is provided, carried by the upper plates 84 for engaging the flange 26, to lock the clamps and the depending channel members 74 in longitudinally adjustable positions upon the flange 26 of the angle iron frame members.

At their lower ends, the channel members 74 have inwardly and laterally extending adjustable stop means 92 which includes a head or abutment surface 94 adapted to engage the outer surface of one of the courses of brickwork, as at 10, this bolt being adjustably connected to the channel member 74 as by means of a pair of nuts

96 engaging the channel member on opposite sides thereof.

As will readily be seen, upon proper adjustment of the member 92 upon the supporting channel member 74 by means of the nuts 96, the abutment head or stop head 94 can be caused to engage the lateral face of a course of brick 10, whereby the channel member 74 can be caused to assume any desired vertical inclination with respect to the vertical plane, and since the channel member 74 is rigidly attached by means of the pin 80 to the angle iron member, the latter including the side wall 24 thereof, can be spaced in vertical alignment with the outer surfaces of the courses of brick 10, and in the vertical plane if desired, by means of spirit levels 100 carried by the body 78.

It will thus be seen that the stop members 92 serve to position the frame of the machine laterally with respect to the courses of brick, whereby the side walls 24 are disposed in vertical alignment with but spaced vertically above the top course 12 of brick, when the machine is positioned on a brick work construction.

Attention is now directed to Figures 3 and 5, wherein it will be seen that one of the angle iron frame members may have secured from a horizontal flange 28 thereof, a guide means 102 as by a fastening means 104.

Attention is now directed more specifically to Figures 10 and 11 for an explanation of the construction of a gauge or ruler which may be employed in conjunction with the machine. Secured to the outer surface of one of the side wall members 24 as by a fastening means 106, is a carrier having a vertically disposed channel or slot 108 in its upper end. Seated in this slot and extending thereabove, is a longitudinally extending strip 110 comprising a gauge or rule, which as shown in Figure 10, at 112, is provided with suitable indicia along its length for designating the proper widths or spacing to be given to the vertical joints between the adjacent edges of the bricks in the additional course of bricks, 114, being added by this machine. It will be noted by an inspection of Figure 10 that joints of varying widths may be readily attained by appropriately spacing the adjacent edges of the bricks of the course 114.

Although the guide bar or gauge 110 has been shown as supported by a plurality of channeled holders 107, it will be understood that the principles of the invention are not limited to the exact construction of holders shown.

Attention is now directed more specifically to Figures 13-15 for an explanation of the construction and operation of the mortar applicator which forms an essential part of this invention. This applicator comprises a means for applying an even layer of mortar to the top course 12, leveling this layer and packing the cracks or joints between the adjacent bricks of the top layer 12 all in readiness for laying an additional layer of bricks 114 thereon.

This applicator consists of a hopper having side walls 118 tapering from a relatively low end wall 120 and a relatively high end wall 122. The applicator 116 is open at its upper and lower ends in order that mortar may be readily applied there into, and that this mortar may rest upon the upper surface of the top course of bricks 12. The end wall 120 is provided with an inwardly overlying flange 124, and with a depending lip 126 which terminates in vertically spaced relation with respect to the lower edge of the walls 118, to provide a discharge opening or orifice whereby

mortar received within the hopper may emerge therefrom and be deposited rearwardly of the applicator as the latter is moved longitudinally of the course of the brickwork.

As shown best in Figure 14, the side walls 118 and also the end wall 122 extend between the guide flanges 42 and are guided thereby as the applicator is moved longitudinally of the frame. These side walls and end wall rest upon the upper surface of the top course 12 to establish a sealing engagement therewith, whereby a layer of mortar indicated at 128 may be deposited thereon inwardly of the edges thereof, in confined relation between the side walls 118. Suitable laterally extending slide blocks 130 are carried at the four extremities of the sides 118, as shown in Figure 1, which slide blocks are adapted to rest upon and slide upon the upper surfaces of the guide means 42. By this means, the lower edges of the sides 118 and 122 do not need to rub directly upon the upper surface of the top course 12, but as will be seen in Figure 14 may be spaced slightly thereabove, while still providing an adequate guiding means or movable form for positioning the layer 128 of mortar upon the bricks.

It will thus be apparent that when the hopper 116 is filled with mortar, and the same is drawn upon the guides 42, that the mortar is discharged from the orifice beneath the edge 126, to deposit the layer 128 and thereby provide the proper bond for the next course of brickwork.

However, it is frequently necessary to provide additional means for forcing the mortar into the cracks between the adjacent bricks of a course. For this purpose, the hopper or applicator 116 is preferably provided with a transversely extending fulcrum or pivot pin 132 which extends through the side walls 118, and upon this pin are pivoted pairs of lever arms 134 and 136. The outer arms 136 are connected at their outer extremities by a cross bar 138 constituting a handle, while a similar handle or cross bar 140 connects the outer extremities of the inner levers 134. Suitably attached in any desired manner to the levers 134 intermediate therein, is a transversely extending tubular member or press chamber 142 having parallel arcuately curved walls, and which member is open at its lower end. The walls of the member 142 are struck out an arc or circle whose center is the axis of the pin or shaft 132.

Intermediate their ends, the inner levers 136 are provided with a transverse bar 144 rigidly attached thereto, which bar carries an arcuate piston rod 146, which extends into the cylinder or press 142, and is provided with a rubber piston or plunger 148 of any suitable construction. A spring 150 is interposed between the supporting member 144 and the head of the tubular member or press chamber 142, for yieldingly urging the levers apart, with the piston in its retracted position as shown in Figure 13.

The operation of this device is as follows. With the hopper filled with mortar, and the parts in the position shown in Figure 13, the applicator is moved longitudinally of the guide rails 42, leaving a leveled coating of mortar 128 therebehind, until the press is positioned successively above each of the joints between adjacent bricks in the top layer 12, and at each joint, the same operation is repeated. The lever 140 is lowered to the position shown in Figure 15, thereby moving the tubular member or press chamber 142 into its lower position, at which time it rests upon the upper surface of two adjacent bricks of the course 12, and seals and

straddles the joint therebetween. The piston is now lowered by moving the levers 136 downwardly against the opposition of the spring 150, in either a single stroke or a series of strokes as desired, as indicated in Figure 15. This downward movement of the piston forces some of the mortar trapped within the chamber 142 downwardly into the cracks or joints between the two adjacent bricks, thereby tightly filling and sealing the vertical joints. Upon release of the handle 138, the spring 150 serves to return the plunger to its uppermost position in the chamber 142.

Upon the completion of the packing of the joints in the top course 12 and the applying of a layer of mortar 128 thereto, an additional course of bricks 114 is then laid as shown in Figures 3 or 5. Since the side walls 24 are spaced at the proper spacing, by means of the above mentioned lateral stops or abutments 92, the individual bricks can be readily placed between the side walls upon the coating 128 of mortar. However, and this is an important feature of the invention, the individual bricks are pressed down between the two side frame members, until the bricks rest upon the guide means 42, which thereby serve as stops to prevent uneven vertical spacing of the bricks of the layer 114. Thus, the bricks are placed in position and positively stopped and positioned at the desired vertical spacing by means of the frame of the machine. When this course of bricks is laid, the handles 20 of the frame clamps are squeezed toward each other, thereby releasing the angle iron side members of the frame together with their support means and lateral stops, whereby the entire device may be raised upward another course, again positioned and the operation repeated.

Indicated at Figure 12 is a further construction within the principles of this invention which may be employed for forming a wall of combined courses of brick and tile. It will be understood that the courses of bricks 10 and 12 have been previously formed by the machine and in the manner set forth hereinbefore, it being understood that a layer of brick is applied of sufficient height to equal that of a layer or course of tile, whereupon the latter is applied, and another series of layers of brick applied, and the operation repeated. When the courses of brick have been completed, the attachment shown in Figure 12 is employed for properly positioning a course of tile. This attachment includes a generally triangular shaped support member 151, having a lower surface 152 disposed to rest upon the upper surface of the top course 12 of bricks, and having a perpendicular, downwardly extending flange 154 which is adapted to engage and slide upon the outer surface of the courses of brick.

Rigidly carried by and extending laterally from the support 151, is a bar 156 to which is detachably secured as by fastening means 158, the upper horizontal arm 160 of a L-shaped bracket 162, whose lower arm 164 is attached to the above mentioned upstanding flange 24 of the angle iron side frame member having a horizontally extending flange 26. This angle iron frame member is provided with the same adjusting means and lateral stop or abutment members referred to in connection with the preceding embodiment of the invention. Likewise, the angle iron is provided with an inwardly extending guide flange 42 as set forth in the pre-

ceding embodiment, and the same supporting toe 68 is likewise provided for resting upon the top-most course of tiles 166 for applying a mortar layer 168 therebetween, in exactly the same manner as the mortar layer 128 previously referred to, and thereafter positioning an additional layer of tiles 170 thereon.

The member 160 is provided with a spirit level 172, whose use will be obvious.

From the foregoing, it is felt that the manner 10 of constructing the machine as well as the method of operating the same will be readily apparent. It will be evident that this invention provides a guide form to insure the proper alignment and positioning of successive courses of 15 brick in forming a brick work construction such as walls or the like, which may be easily adjusted for leveling and for plumbing as desired, which may be very quickly applied to or removed from a brickwork construction with a minimum of effort, and which is readily adjusted for effecting mortar joints between courses of varying thicknesses as desired.

Further, it will also be evident that there is 20 provided a novel frame construction which not only serves to quickly and accurately apply a mortar layer of actuate predetermined dimensions upon the top course of brick for bonding the additional course thereto, but also which 25 serves to insure that the additional course of brick will be properly spaced vertically from the top course. Further, not only does the applicator insure that the mortar layer shall be evenly and uniformly spread, but it includes 30 means for positively packing and compressing the mortar into the cracks or joints between the bricks of the top course.

Further, it will be evident that the machine 35 may be readily constructed to accommodate and construct walls or brick constructions of varying widths; and may be also advantageously employed to erect walls or constructions having both brick and tile layers.

From the foregoing, the manner of constructing 40 and operating the invention will be readily understood and further explanation is deemed to be unnecessary.

However, since numerous modifications and 45 equivalents will readily occur to those skilled in the art after a consideration of the foregoing 50 specification and accompanying drawings, it is not desired to limit the invention to the exact

construction shown and described, but all suitable modifications and equivalents may be resorted to, falling within the scope of the appending claims.

Having described the invention, what is claimed as new is:

1. In a brick laying machine, a frame comprising a pair of side walls for embracing the top-most course of a brickwork construction, support members for supporting said side wall members upon the top of a lower course of brickwork, inwardly extending flanges on said side wall members for supporting and positioning an additional course of brickwork above said top course, said side wall members having clamps slidably longitudinally thereon, said support members being carried by said clamps.

2. The combination of claim 1 wherein said support members include vertically extending rods having inward toes at their lower ends for insertion between said lower course and the immediately overlying course, said rods being adjustably secured to said clamps for sliding vertical adjustment therein.

3. The combination of claim 1 including transverse clamp bars, levers intermediately pivoted to said clamp bars, said side wall members being carried by the lower ends of said levers for pivotal movement therewith, spring means terminally engaging said levers and clamp bars for yieldingly urging said side wall members towards each other.

4. The combination of claim 3 including abutment means comprising a plurality of downwardly extending channel-shaped members carried by additional clamps on said side wall members.

JOHN D. KIRSCHMANN.
